Charles F. Smith, English, W. Va.

Application October 29, 1936, Serial No. 108,283

7 Claims. (Cl. 104—257)

This invention relates to an automatic safety scotch mechanism for mine cars and it aims to provide a novel construction capable of use in connection with any railway car, although especially designed to make coal mining safer.

A prime object is to provide such a construction having a scotch block adapted to prevent the car from running off of a rail and a movable scotch block which is positioned automatically through engagement of a car with the stationary or first mentioned scotch block.

The more specific objects and advantages will become apparent from a consideration of the description following taken in connection with the accompanying drawings illustrating an operative embodiment.

In said drawings:—

Figure 1 is a view in side elevation showing my improvements in position about to be engaged by a car;

Figure 2 is a plan view of the parts in the condition of Figure 1;

Figure 3 is a reverse side elevation to Figure 1;

Figure 4 is an end elevation looking from the right of Figure 2;

Figure 5 is a detail section taken on the line 5—5 of Figure 1;

Figure 6 is a side elevation showing the improvements in operative condition holding a car;

Figure 7 is a plan view of the parts of Figure 6;

Figure 8 is a detail section taken on the line 8—8 of Figure 6, and

Figure 9 is a detail section taken on the line 9—9 of Figure 6.

Referring specifically to the drawings wherein like reference characters designate like or similar parts, 10 designates one rail or track of a railway for mine cars, a wheel of one of which is suggested as at 11, said rail and wheel being of conventional structure.

In carrying out the invention, a scotch block is employed at 12, which is cut-out as at 13, in order to intimately fit against the rail and extend above it, the portion of the block above the rail being concave as at 14 to conform with the periphery of the wheel 11. Said block 12 is adapted to be fastened to the rail in a stationary manner and to this end a detachable clamp block 15 is employed at 16, cut away to intimately fit the rail 10 at 11, and jointly with the block 12 to be clamped thereto by means of a bolt 17 passing loosely through them. On the bolt 17, a lever 18 is loosely positioned and beyond the same, a nut 19 is screw threaded. Those surfaces of the

block 12 and clamp 15 which engage the ball 20 of the rail 10, are preferably serrated or roughened as at 21, so that they may engage the ball with less danger of slippage.

An arm 23 extends rigidly from the block 12 and to the free end of such arm on a vertical pivot or bolt 24, a movable scotch block 25 is fastened, preferably through the medium of an arm 26. Arm 26 has a lug 27 thereon to which a lever or bar 28 is pivoted by means of a vertical bolt 29. To such lever 28 a trigger member 30 is pivoted by means of an element 31 on a horizontal axis and which trigger is pivoted to a rod 32, preferably slightly curved as shown and having an abutment 33 at its outer end, the trigger 30 being slideable along the rod 32 as well as pivotally mounted on the same.

It will be noted that the clamp member 15 is beveled or cut away as at 34 and that the lever 18 is beveled or cut away as at 35.

Normally the mechanism is set in the position best shown in Figures 1 to 4. The movable scotch block 25 is thus out of the path of movement of the car. The wheel 11 will move on the track or rail 10 past the scotch block 25 and engage the trigger 30, moving it on its axis 32 and causing it to move the lever 28 and scotch block 25 into alignment with the scotch block 12, on the opposite side of the wheel, thus automatically functioning. The wheel as a result, will be held by the block 12 from rolling off the end of the rail and it will also be held from movement in the opposite direction by the scotch block 25.

Attention is called to the fact that as the wheel engages the surface 14, the flange thereof will enter the cut away portion 34, thus acting as a wedge therein and moving the block 12 and clamp 15 into tighter engagement with the rail, to guard against slippage or displacement thereof.

The scotch block 25 may be manually released by the miner, to the position best shown in Figure 2, by swinging the lever 28 outwardly on its axis and at the same time pulling the lever so that the trigger 30 rocks on the rod 32. While the wheel is still engaged with the scotch block 12, the scotch block 25 may be released by the miner, by pulling the lever 28 outwardly at its free end, the length of the rod 32 permitting the necessary movement, especially to enable the parts to slip past the drum of the wheel. By using the lever to pull the trigger out and return the scotch block 12 to its open position, the car having the wheel 11 can be pulled or moved away from the block 12 without endangering the miner. In cases where the weight of the car is

still against the scotch block 25, the lever 28 may be pulled out into engagement with the abutment 33 and then when the scotch 25 is released, the lever can be pulled back into ready or open position and then when the car has been removed, the lever is pushed back into normal position as in Figure 2.

In some instances it is necessary to apply a scotch to a rail having no open end. The bevel edge 34 of the clamp, with the lever 18 having the bevel edge 35 permits relative tilting of these parts so that the device may be attached without disconnecting the rail.

Said lever 18 is also beveled at 35 to permit the release of the clamp so that it may be placed on or removed from the rail anywhere without having to slip it over the end of the rail. It is clear that the openings in the clamp 15 and lever 18, through which the bolt 17 passes, are of such size to permit the movements mentioned.

Various changes may be resorted to provided they fall within the spirit and scope of the invention.

I claim as my invention:—

1. A device of the class described having a scotch block, means to secure said scotch block to a rail, a second scotch block movably secured to the first mentioned scotch block, and means operable through movement of a wheel to engage the first mentioned scotch block, to apply the second mentioned scotch block to the rail on the side of the wheel opposite to the first mentioned scotch block.

2. A device of the class described having a scotch block, means to secure said scotch block to a rail, a second scotch block movably secured to the first mentioned scotch block, means operable through movement of a wheel to engage the first mentioned scotch block, to apply the second mentioned scotch block to the rail on the side of the wheel opposite to the first mentioned scotch block, the first mentioned means comprising a clamp, said clamp and first mentioned scotch block being engageable with a rail.

3. A device of the class described having a scotch block, means to secure said scotch block to a rail, a second scotch block movably secured to the first mentioned scotch block, means operable through movement of a wheel to engage the first mentioned scotch block, to apply the second mentioned scotch block to the rail on the side of the wheel opposite to the first mentioned scotch block, the first mentioned means comprising a clamp, said clamp and first mentioned scotch block being engageable with a rail, a bolt passing through the first mentioned scotch block and clamp, said clamp having a beveled upper edge portion providing clearance to receive the flange of a wheel to wedge the same into engagement with a rail.

4. A device of the class described having a scotch block, means to secure said scotch block to a rail, a second scotch block movably secured to the first mentioned scotch block, means operable through movement of a wheel to engage the

first mentioned scotch block, to apply the second mentioned scotch block to the rail on the side of the wheel opposite to the first mentioned scotch block, the first mentioned means comprising a clamp, said clamp and first mentioned scotch block being engageable with a rail, a bolt passing through the first mentioned scotch block and clamp, said clamp having a beveled upper edge portion providing clearance to receive the flange of a wheel to wedge the same into engagement with a rail, a nut on said bolt, a lever on the bolt between the nut and clamp, said lever having a beveled upper end, permitting movement thereof to afford clearance between the clamp and first mentioned scotch block.

5. A device of the class described having a scotch block, means to secure said scotch block to a rail, a second scotch block movably secured to the first mentioned scotch block, means operable through movement of a wheel to engage the first mentioned scotch block, to apply the second mentioned scotch block to the rail on the side of the wheel opposite to the first mentioned scotch block, the second mentioned means including a lever automatically movable by the wheel, for the application of the second mentioned scotch block, said lever being manually operable to release the second mentioned scotch block.

6. A device of the class described having a scotch block, means to secure said scotch block to a rail, a second scotch block movably secured to the first mentioned scotch block, means operable through movement of a wheel to engage the first mentioned scotch block, to apply the second mentioned scotch block to the rail on the side of the wheel opposite to the first mentioned scotch block, the second mentioned means including a lever automatically movable by the wheel, for the application of the second mentioned scotch block, said lever being manually operable to release the second mentioned scotch block, an arm extending from the first mentioned scotch block, and means pivoting the second mentioned scotch block to the arm on a vertical axis.

7. A device of the class described having a scotch block, means to secure said scotch block to a rail, a second scotch block movably secured to the first mentioned scotch block, means operable through movement of a wheel to engage the first mentioned scotch block, to apply the second mentioned scotch block to the rail on the side of the wheel opposite to the first mentioned scotch block, the second mentioned means including a lever automatically movable by the wheel, for the application of the second mentioned scotch block, said lever being manually operable to release the second mentioned scotch block, a trigger pivoted to the lever adapted for direct engagement with the car wheel, and a rod on the first mentioned scotch block on which the trigger is pivotally and slidably mounted.
